Primary Examiner — Marianne Pandozzi(74) *Attorney, Agent, or Firm* — Michael P. Mazza, LLC(57) **CLAIM**

I claim the ornamental design for the combination water dispenser and beverage brewer, as shown and described in the drawings.

DESCRIPTION

FIG. 1 is a front and side perspective view of a combination water dispenser and beverage brewer showing my new design;

FIG. 2 is a front view thereof;

FIG. 3 is a right side view thereof;

FIG. 4 is a left side view thereof;

FIG. 5 is a rear view thereof;

FIG. 6 is a top plan view thereof; and,

FIG. 7 is a bottom plan view thereof.

The broken lines in the drawings are included for the purpose of illustration and form no part of the claimed design.
